UNITED STATES PATENT OFFICE.

HUGO JUNKERS, OF AACHEN-FRANKENBURG, GERMANY.

LIQUID-FUEL FURNACE.

Application filed January 15, 1925, Serial No. 2,599, and in Germany March 7, 1924.

My invention refers to furnaces and more especially to liquid fuel burners adapted for use in furnaces for household use, including stoves and kitchen ranges, in which the fuel, instead of being injected together with air or steam, is distributed on suitably arranged surfaces and evaporated for combustion with the air flowing past such surfaces. It is an object of my invention to provide a furnace of this kind which can be operated more easily and has a higher efficiency than similar furnaces hitherto devised.

In the burner according to the present invention a grate mounted preferably in horizontal position in a vertical air flue is supplied with liquid fuel by capillary action, members, which may consist of porous material such as for instance earthenware, being connected with such grate and serving for conveying the liquid fuel to the places of combustion. Preferably the grate is perforate and made integral with the capillary members, and in a preferred form of my invention several such members spread apart and having the form of an inverted U are supported in troughs supplied with liquid fuel and have formed their upper edges with serrated lateral extensions, the extensions of a plurality of such members forming a kind of perforate grate.

In the drawings affixed to this specification and forming part thereof several forms of a burner embodying my invention are illustrated diagrammatically by way of example.

In the drawings—

Fig. 1 is a vertical section and

Fig. 2 is a horizontal section of the first form,

Fig. 3 being a vertical section of some of the grate elements.

Fig. 4 is a vertical section and

Fig. 5 a plan view of a second form,

Fig. 6 being a partial vertical section at right angles to Fig. 4 with the furnace walls omitted.

Figs. 7, 8 and 9 are vertical sections of these further modifications;

Fig. 10 is an end view of still another form.

Referring first to Figs. 1-3, 1, 1 are masonry walls confining between them an angular air flue 2, 3. The front wall has an air inlet 4, an opening 5 closed by a hand-operated air valve 6 and between the two a

row of narrow apertures 7 through which extend fuel supply pipes 8 having mounted on their outer ends a channeled fuel container 9 fed by a pipe 10. The inner end of each pipe 8 forms part of a narrow trough 11, the end walls of which are fitted with supports 12. Brackets 13 mounted on the furnace walls serve to support the troughs 11. In each trough is inserted from above a plate-shaped grate member 14 of porous material, for instance earthenware, having formed on either side of its top edge rows of lateral extensions 15 having about the outer appearance of racks. Four such troughs 11 and members 14 are arranged side by side in the air flue 2, the lateral extensions 15 of adjoining members almost contacting with each other and forming a perforate grate extending in the plane of the bottom edge of the slot 16 in the air valve 6, so that the air entering through this slot will flow past the top edges of the members 14 which form the grate.

The liquid fuel supplied to the troughs 11 rises by capillary action in the member 14 and oozes out on the surfaces of the extensions 15. The ascending air current entering through the inlet 4 and rising in the interstices left between the members 14, as shown by the arrow in Fig. 3, causes the fuel on the surface of these members to evaporate and on the grate formed by the lateral projections 15 a mixture of fuel and air is formed which burns in the air introduced through the slot 16.

In the modification shown in Figs. 4-6 the porous members 17 have the form of inverted U's, their depending arms 18 being supported on ledges 19 forming part of the side walls of a pair of separate troughs 20 extending at right angles to the grate members which are again fitted with rows of lateral extensions 21 on their top edges. Here the air causing evaporation of the fuel flows in horizontal direction between the pairs of arms 18 and vertically upwards between adjoining members, as shown by the arrows in Fig. 4.

Figs. 7, 8 and 9 show simpler forms of porous grates.

In the form disclosed in Fig. 7 a perforate earthenware plate 22 has a porous arm 23 formed on its bottom surface, this arm extending into a trough 24, while the bottom edge of the inclined plate 22 is submerged

in liquid fuel contained in another trough 25, so that fuel is conveyed by capillary action in two places.

Fig. 8 illustrates a horizontal plate-shaped 5 perforate grate 26 with a plurality of porous arms 27 extending into troughs 28.

In Fig. 9 is disclosed a vertically mounted perforate grate 29 having its bottom edge supported in a trough 30 filled with fuel, an 10 angle-shaped arm or arms 31 fed by another trough 32 supplying fuel to the upper portion of the grate.

Fig. 10 shows a modified form of the porous member disclosed in Fig. 4, three arms 15 33 being supported in three separate troughs 34 and offering to the air of evaporation two parallel horizontal passages.

I wish it to be understood that I do not desire to be limited to the exact details of 20 construction shown and described, for obvious modifications will occur to a person skilled in the art.

I claim:—

1. Liquid fuel burner comprising a liquid fuel supply and a grate bar of capillary structure extending substantially in horizontal position above and spaced from said fuel supply, a substantially vertical extension of said bar also having capillary structure extending into said fuel supply and serving to feed liquid fuel to said bar.

2. Liquid fuel burner comprising a plurality of liquid fuel supplies and grate bars extending substantially in horizontal position above and spaced from said fuel supplies, a substantially vertical extension of each bar having capillary structure extending into one of said fuel supplies. 35

3. Liquid fuel furnace comprising a plurality of juxtaposed grate bars, teeth-like 40 lateral extensions on said bars, a supply of liquid fuel below and spaced from said bars and an extension of capillary active material on each bar extending into said fuel supply. 45

4. Liquid fuel furnace comprising a grate bar, a plurality of supplies of liquid fuel below and spaced from said grate bar and a substantially vertical capillary portion of said grate bar having an indenture forming 50 a plurality of arms, each arm extending into one of said fuel supplies.

5. Liquid fuel furnace comprising a grate bar, a plurality of supplies of liquid fuel below said bar, spaced apart to allow air to 55 ascend between them and a plurality of extensions of capillary material of said grate bar, each extension extending into one of said fuel supplies.

In testimony whereof I affix my signature.

HUGO JUNKERS.
